[57] CLAIM

The ornamental design for a chair/ottoman base, as shown and described.

DESCRIPTION

FIG. 1 is a perspective view of a first embodiment of a chair/ottoman base embodying my new design, with a chair supported by the base being shown in phantom lines "for environmental purposes only and forming no part of the claimed design;"

FIG. 2 is a top plan view of the chair/ottoman base of FIG. 1;

FIG. 3 is a bottom plan view of the chair/ottoman base of FIG. 1;

FIG. 4 is a left side elevational view of the chair/ottoman base of FIG. 1, which is identical to the right side elevational view thereof;

FIG. 5 is a front elevational view of the chair/ottoman base of FIG. 1, which is identical to the rear elevation view thereof;

FIG. 6 is a perspective view of a second embodiment of a chair/ottoman base embodying my new design;

FIG. 7 is a top plan view of the chair/ottoman base of FIG. 6;

FIG. 8 is a bottom plan view of the chair/ottoman base of FIG. 6;

FIG. 9 is a left side elevational view of the chair/ottoman base of FIG. 6, which is identical to the right side elevational view thereof; and,

FIG. 10 is a front elevational view of the chair/ottoman base of FIG. 6, which is identical to the rear elevation view thereof.
